UNITED STATES PATENT OFFICE.

DANIEL F. LEPLEY, OF CONNELLSVILLE, PENNSYLVANIA.

CLAY-GRINDING PAN.

SPECIFICATION forming part of Letters Patent No. 772,621, dated October 18, 1904.

Application filed September 4, 1903. Serial No. 171,991. (No model.)

To all whom it may concern:

Be it known that I, DANIEL F. LEPLEY, a citizen of the United States, residing at Connellsville, in the county of Fayette and State 5 of Pennsylvania, have invented a new and useful Clay-Grinding Pan, of which the following is a specification.

This invention relates to mechanism employed in connection with the manufacture of 10 silica bricks, such as are now used as substitutes for ordinary fire-clay.

The principal object of the invention is to provide mechanism for grinding or reducing the sandstone to the form of powder and at 15 the same time mixing it with a binding agent, which may be in the form of ordinary fire-clay or similar material.

A further object of the invention is to provide means for removing the finished material 20 from the grinding-pan; and in this connection a further object is to provide improved means for manipulating the dipper.

A still further object of the invention is to provide a dipper-actuating mechanism in 25 which provision is made for insuring the further removal of all the contents of the dipper at each operation and to provide controlling means whereby the speed of movement may be regulated.

With these and other objects in view the invention consists in the novel construction and arrangement of parts hereinafter described, illustrated in the accompanying drawings, and particularly pointed out in the appended 35 claims, it being understood that various changes in the form, proportions, and minor details of construction may be made without departing from the spirit or sacrificing any of the advantages of the invention.

In the accompanying drawings, Figure 1 is a transverse sectional elevation of a grinding-pan and dipper arranged and constructed in accordance with the present invention. Fig. 2 is a plan view of the same. Fig. 3 is a detail perspective view of the dipper proper. Fig. 4 is an elevation of a portion of the dipper-actuating mechanism. Fig. 5 is a longitudinal sectional elevation of the dipper-actuating mechanism on the line 5 5 of Fig. 4.

Fig. 6 is a sectional plan view of the same on 50 the line 6 6 of Fig. 5.

Similar numerals of reference are employed to indicate corresponding parts throughout the several figures of the drawings.

Referring to the drawings, 1 indicates a 55 suitable frame having bearings for the reception of the vertically-disposed shaft 2, which extends through a horizontally-disposed grinding-pan 3 and is secured thereto in any suitable manner in order that rotative movement may be imparted to the pan through 60 bevel-gears 4.

The grinding-pan is provided with an annular trough 5, having tapering walls in the form of concentric annular flanges 6, which 65 are secured to and rotate with the pan. In this trough are arranged two grinding-rollers 7, having central spindles 8, mounted in bearings at the ends of freely-movable rocker-arms 9 and serving by their weight to grind 70 the material as the latter is carried around by the pan.

In the treatment of material for the manufacture of silica bricks it is necessary to reduce the sandstone and at the same time mix 75 the same with a binding agent in order to hold the ground material in the form of bricks. Owing to the abrasive qualities of the material, the machinery employed will ordinarily last but a short period of time, and difficulty 80 is also experienced in the removal of the material from the grinding-pan after the reducing and mixing operations have been completed. At the present time this material is removed by hand-labor and the operation is slow and 85 expensive.

In carrying out the present invention provision is made for the gradual removal of all of the material without loss of time and without excessive wear on any of the parts of the 90 apparatus. For this purpose there is employed a dipper 10, having a carrying-arm 11, mounted on a horizontally-disposed shaft 12. The shaft is mounted in suitable bearings at one side of the grinding-pan and is provided with a pinion 13, with which meshes a vertically-movable rack 14, held in a guide 15, an adjustable wear-plate 16 being held against

the rear face of the rack by set-screws 17 and serving to hold the rack in proper position with respect to the pinion. To the rack are secured two plunger-rods 18 and 19, the lower rod carrying a piston 20, arranged within a pressure-cylinder 21, having a suitable controlling-valve 21' for regulating the admission of an actuating fluid, which may be in the form of water, air, or other fluid. The valve 10 is connected to the lever 21' in the manner shown by dotted lines in Figs. 1 and 5, the lever being disposed in convenient position for manipulation by a workman, so that the actuating fluid may be directed either through 15 the upper or the lower end of the cylinder. The upper plunger-rod 18 carries the piston 22 disposed within a cylinder 23, that serves as a dash-pot, being filled with oil or other liquid, and the opposite ends of said cylinder 20 being placed in communication with each other by means of pipes 24 and 25. These pipes are provided with controlling-valves 26 for regulating the flow of the fluid between opposite ends of the cylinder and are further provided with check-valves 27, opening, respectively, in opposite directions. The check-valve on the pipe 24 opens to permit the passage of the fluid from the lower to the upper end of the cylinder, while the check-valve on 30 the pipe 25 permits the passage of fluid in an opposite direction. By this means the fluid is compelled to pass through one or other of the pipes in accordance with the direction of movement of the piston 22. The valves 26 will control the speed of movement and may be arranged to offer greater resistance in one direction than in the other, inasmuch as the load varies in the two actuating movements. 35

During downward movement of the rack 14, 40 which occurs when the dipper is carrying the load from the pan, the fluid in the lower portion of the cylinder 23 flows upward through the pipe 24, the valve 26 having been adjusted in order to prevent the rapid passage of the fluid, so that the cylinder and piston will at this time act as a dash-pot to retard the movement of the dipper, the liquid flowing slowly 45 through the pipe 24 to the upper end of the cylinder. When the rack is traveling in the opposite direction, the fluid flows from the upper end of the cylinder to the lower end thereof through the pipe 25, and the controlling-valve in such pipe need not be closed to such an extent as the valve of pipe 24, inasmuch as the dipper is then emptied and only 50 its weight need be counterbalanced by the dash-pot.

The controlling-valve of cylinder 21 is operated by means of the hand-lever 21', and on 60 the admission of fluid under pressure the dipper will be moved from a normally inoperative position to a point within the pan, and as said dipper is open in a direction opposite to that in which the pan is moving it will

gradually be filled by the ground material. 65 When filled, the valve is moved in the reverse direction and shaft 12 is rotated to an extent sufficient to raise the dipper and deposit its contents on the ground or in a suitable receptacle at the side of the pan. 70

In order to limit the range of movement of the dipper, the end of shaft 12 is provided with a collar 28, in which is secured an arm 29, that alternately comes in contact with stops 30 and 31 in the form of blocks carried 75 by a segment 32 on or forming a part of the main frame. This segment is provided with curved slots 33, through which extend stop-block-attaching bolts 34, in order that the blocks may be adjusted. On the downward 80 movement of the dipper the arm 29 makes contact with the stop 31 in order to prevent contact between the dipper and the upper surface of the pan, as such contact must be prevented in order to avoid injury to both members 85 from the abrasive action of the material being operated upon. In the opposite direction of movement arm 29 comes into contact with stop-block 30 and effects a sudden violent stop, so that all of the contents of the pan will be 90 thrown out.

It will be understood that the stop-blocks are intended not only to limit the extent of movement of the dipper, but also to suddenly arrest the movement of the dipper, especially during the dumping operation, so that all of the contents of the dipper will be ejected in a more or less violent manner. 95

It is obvious that the extent of movement of the dipper may be regulated by the controlling-valve of cylinder 21, so that said dipper may be successively introduced to successively lower levels during the removing operation, and thus to some extent relieve the dipper from the action of the abrasive material. 100 105

In lieu of the trough-shaped pan herein illustrated the pan may be in the form of a flat disk having a single marginal flange in order to prevent the escape of the material 110 being operated upon. 115

Having thus described the invention, what is claimed is—

1. The combination with a grinding-pan, of a pivotally-mounted dipper, means for actuating the dipper, and means for suddenly checking the dumping movement thereof to thereby eject the contents of the dipper. 115

2. The combination with a grinding-pan, of a horizontally-disposed shaft arranged adjacent to the periphery of the pan, a dipper carried by the shaft and movable thereby to a filling position within the pan, and to a dumping position upward and outward beyond the periphery of the pan, and means for stopping the movement of the dipper in a downward direction and prevent frictional contact of said dipper with the upper surface of the pan. 120 125

3. The combination with a grinding-pan, of a pivotally-mounted dipper, mechanism for moving the dipper into and out of the pan, and a retarding means tending to resist movement of the dipper and said mechanism.

4. The combination with a grinding-pan, of a pivotally-mounted dipper, mechanism for moving the dipper into and out of the pan, a retarding means serving to resist movement of the dipper in both directions, and means for adjusting the degree of such resistance in proportion to the load.

5. The combination with a grinding-pan, of a shaft, a dipper carried thereby, a pinion on the shaft, a rack intermeshing with the pinion, and means for operating said rack.

6. The combination with a grinding-pan, of a shaft, a dipper carried by the shaft, means for operating the shaft, an arm secured to and movable with said shaft, and a stop-block disposed in the path of movement of the arm and adapted to suddenly check the movement of the dipper.

7. The combination with a grinding-pan, of a shaft, a dipper carried by the shaft, a pinion on said shaft, a rack intermeshing with the pinion, a pair of plunger-rods secured to the rack, pistons carried by the plunger-rods, an actuating - cylinder receiving one of the pistons, a dash-pot receiving the opposite piston, and means for limiting the rotative movement of the shaft.

8. The combination with a grinding-pan, of

a shaft, a dipper carried by the shaft, a pinion on the shaft, a rack intermeshing with the pinion, a pair of plunger-rods secured to the rack, pistons carried by the plunger-rods, an actuating - cylinder receiving one of the pistons, a dash-pot cylinder receiving the second piston, and valved by-passes connecting the opposite ends of the dash-pot cylinder and provided with check-valves opening respectively in opposite directions.

9. The combination with a grinding-pan, of a shaft, a dipper secured to the shaft, a pinion carried by the shaft, a movable rack intermeshing with said pinion, an adjustable guide for the rack, a slotted segment disposed adjacent to the shaft, a pair of stop-blocks carried by said segment, and a stop-lever carried by the shaft and adapted to engage said stop-blocks.

10. A mill for grinding clay, &c., having in combination therewith, a shaft, an arm secured to said shaft, a scoop carried by said arm, means for rotating the shaft to invert the scoop and shift it from receiving to discharging position, and a stop for arresting the movement of the scoop.

In testimony that I claim the foregoing as my own I have hereto affixed my signature in the presence of two witnesses.

DANIEL F. LEPLEY.
